UNITED STATES PATENT OFFICE

2,642,998

SUPPORTING RACK AND HOLDER FOR MORTAR HODS

Ira E. Boyd, Sr., Warren, Ohio

Application September 8, 1950, Serial No. 183,881

2 Claims. (Cl. 211—60)

1

This invention relates to supports, and more particularly to a supporting rack and holder for mortar hods.

An object of this invention is to provide a supporting rack and holder for mortar hods which is adapted for assembly with and securement to a mortar box.

Another object of this invention is to provide a supporting rack and holder for mortar hods which may be assembled with a mortar box along any or all sides of the box with speed and facility.

A further object of this invention is to provide a supporting rack and holder for mortar hods which is relatively simple in structure and cheap to manufacture.

The above and still further objects and advantages of the invention will become apparent upon consideration of the following detailed description of the invention, when taken in conjunction with the accompanying drawings, wherein:

Figure 1 is a front elevational view of the supporting rack and holder for mortar hods of the present invention, shown supported on a mortar box;

Figure 2 is an elevational view taken along the line 2—2 of Figure 1, with parts broken away and shown in section; and

Figure 3 is a perspective view of a supporting rack forming a part of the supporting rack and holder for mortar hods of the present invention.

Referring now more particularly to the drawings, wherein like reference numerals have been used throughout the several views to designate like parts, there is shown the mortar hod supporting rack and holder of the present invention, generally designated by the reference numeral 10 supported on mortar box 11.

The supporting rack and holder 10 comprises the supporting rack 12 Figure 3 which includes a pair of U-shaped frame members 13, 14 disposed in side by side spaced relation with respect to each other and each having vertically disposed bights 15, 16 and horizontally disposed legs 17, 18 and 19, 20. The free ends of the legs 18, 20 of the frame members 13, 14 are turned inwardly and downwardly to a vertical position to form depending flanges, the flanges being designated by the reference numerals 21, 22.

Extending between the depending flanges 21, 22 is a first cross bar 23 which is secured therebetween by any suitable means such as welding.

Extending between the bights 15, 16 of the U-shaped frame members 13, 14 are the spaced cross bars 24, 25. The cross bar 24 is secured contigu-

2

ous to the legs 18, 20 of the U-shaped frame members in substantially spaced parallel relation with respect to the cross bar 23 while the cross bar 25 is secured contiguous to the lower ends of the bights 15, 16. Positioned in spaced parallel relation with respect to the cross bar 25 is a stop bar 26 which is secured between the legs 17, 19 of the U-shaped frame members 15, 16.

Disposed in side by side spaced relation with respect to each other are the combination brace and abutment elements, designated generally by the reference numerals 28, 29. Since each of the combination brace and abutment elements is of a like structure, it will suffice to describe only one in detail. The element 28 includes a first section disposed at an angle with respect to the leg 17 of the U-shaped frame member 13, the section being designated by the reference numeral 30 and having one end secured to the bight 15 and having the other end secured to the leg 17 intermediate the cross bar 25 and stop bar 26, an intermediate section which underlies the stop bar 26 and is secured thereto and in abutting relation with respect to the leg 17, the intermediate section being designated by the reference numeral 31, and a vertically extending abutment section 32 which is spaced from the free end of the leg 17 and is connected to the intermediate section 31 by a connecting section 33.

Extending between the leg 18 and the bight 15 of the U-shaped frame member 13 and between the leg 20 and the bight 16 of the U-shaped frame member 14 are the brace bars 34, 35. The brace bars 34, 35 impart additional rigidity to the various structural components of the supporting rack 12.

It is to be noted that the entire assembly of the supporting rack 12 is fabricated of suitable strap steel or iron which is extremely durable and of a thickness to give it the desired strength. The various components of the supporting rack, as previously pointed out, are secured together by means of welding or any other suitable securing means.

Supported within the rack 12 is a holder 33 which has one end provided with a V-shaped cut 36 for the support of the V-shaped trowel of the mortar hod 37 and has the other end resting on the ground surface against the stop bar 26 intermediate the legs 17, 19 of the U-shaped frame members 13, 14.

Referring now with particularity to Figures 1 and 2, there is shown the supporting rack 12 supported on the mortar box 11, the mortar box

including at least one vertically disposed wall 38 and a bottom 39. In effecting the assembly of the supporting rack 12 with the mortar box 11, the depending flanges 21, 22 are engaged over the upper end of the vertical wall 38 to abut against the inner surface thereof while the free ends of the legs 17, 19 are inserted beneath the bottom 39 of the mortar box 11 to a position wherein the abutment plates 32 of the combination brace and abutment elements 28, 29 bear against the outer face of the vertical wall 38. It is to be noted that the spacing of the depending flange 22 and the abutment plate 32 are selected so that the rack 12 is supported in a substantially rigid position against displacement with respect to the mortar box 11.

From the foregoing, it is relatively apparent that the rack 12 can be moved to any point on the sides of the mortar box 11 so that the hod can be easily loaded. Since the rack is relatively compact it will not take up much space when being transported from place to place on vehicles. It is to be further noted that any number of holders 33 can be supported within the rack 12 by either making the length of the rack 12 much longer or increasing the spacing between the U-shaped frame members 13, 14 or by substantially decreasing the width of the holder 33.

Although only one embodiment of the supporting rack and holder for mortar hods has been described, it is readily apparent that numerous modifications can be made without departing from the spirit of the invention as set forth in the appended claims.

What I claim is:

1. A mortar hod supporting rack including a pair of U-shaped frame members disposed in side-by-side spaced relation with respect to each other with their bights vertically disposed and each having the free end of one leg turned in-

wardly to form a depending flange, a pair of spaced cross bars respectively extending between and secured to the bights of said U-shaped frame members contiguous to the respective ends of the bights, and a stop bar extending between the other legs of said U-shaped frame members in spaced parallel relation with respect to the adjacent one of said pair of cross bars and secured to said other legs inwardly of their outer ends.

2. A mortar hod supporting rack including a pair of U-shaped frame members disposed in side-by-side spaced relation with respect to each other with their bights vertically disposed and each having the free end of one leg turned inwardly to form a depending flange, a pair of spaced cross bars respectively extending between and secured to the bights of said U-shaped frame members contiguous to the respective ends of the bights, a stop bar extending between the other legs of said U-shaped frame members in spaced parallel relation with respect to the adjacent one of said pair of cross bars and secured to said other legs inwardly of their outer ends, and an abutment spaced from the free end of each of said other legs of said U-shaped frame member and mounted upon said other legs forwardly of the stop bar, so as to be disposed between the stop bar and the free ends of said other legs.

IRVING E. BOYD, SR.
